US0D1036249S

(12) **United States Design Patent** (10) Patent No.: **US D1,036,249 S**
(45) Date of Patent: ** Jul. 23, 2024

(54) **FASTENING RING**

- (71) Applicant: **BizLink Industry Germany GmbH**,
Roth (DE)
- (72) Inventors: **Torsten Denk**, Steinbach-Hallnberg
(DE); **Sebastian Konietzko**, Bad
Liebenstein (DE); **Veit Wagner**,
Zillbach (DE); **Karina Weißensee**, Suhl
(DE); **Christian Gießler**,
Brotterode-Trusetal (DE)
- (73) Assignee: **BizLink Industry Germany GmbH**,
Roth (DE)
- (**) Term: **15 Years**
- (21) Appl. No.: **35/515,718**
- (22) Filed: **Sep. 1, 2022**

(80) **Hague Agreement Data**

- Int. Filing Date: **Sep. 1, 2022**
Int. Reg. No.: **DM/225058**
Int. Reg. Date: **Sep. 1, 2022**
Int. Reg. Pub. Date: **Dec. 9, 2022**

(30) **Foreign Application Priority Data**

- Mar. 1, 2022 (EM) 008874721-0001
Mar. 1, 2022 (EM) 008874721-0002

(51) **LOC (14) Cl.** **08-08**

(52) **U.S. Cl.**
USPC **D8/396**
